TUFTING BUTTON

Wilfred B. Mathewson, North Weymouth, Mass.,
assignor to United Mattress Machinery Company, Quincy, Mass., a corporation of Maine

Application March 20, 1933. Serial No. 661,647

4 Claims. (Cl. 24—90)

This invention relates to tufting buttons such as are used for tufting mattresses, cushions, upholstery and the like.

One method of tufting mattresses, cushions and the like is to insert through the mattress, cushion or other article a loop of tufting cord or tufting tape with the two sides of the loop spaced from each other and then to tie the ends of the cord or tape together. This operation produces a knot 10 on the outside of the mattress or other article at one end of the loop. To complete the tufting operation a tufting button is frequently attached to the exposed ends of the loop on one or both sides of the mattress or other article.

15 The presence of the knot at one end of the loop on the outside of the mattress makes it difficult, if not impossible to apply an ordinary tufting button to the knotted end of the loop and consequently some mattress manufacturers have resorted to the operation of drawing the knot 20 through the ticking of the mattress into the interior thereof in order to enable a tufting button to be applied to each end of the loop.

It is one of the objects of the present invention 25 to provide an improved form of tufting button which is constructed so that it may readily be applied to the knotted end of the loop of tufting cord and when so applied the knot will be located within the tufting button and thus concealed from view.

30 In order to give an understanding of the invention I have illustrated in the drawing a selected embodiment thereof which will now be described after which the novel features will be pointed out in the appended claims.

35 Fig. 1 is a fragmentary sectional view through a mattress or similar article showing a loop of tufting cord inserted through the mattress and knotted;

40 Fig. 2 is a similar view showing my improved tufting button applied to both ends of the loop of tufting cord;

Fig. 3 is back side view of a tufting button embodying my invention;

45 Fig. 4 is a similar view showing it applied to the knotted end of a loop of tufting cord;

Fig. 5 is a side view of a tufting button embodying my invention;

Fig. 6 is a section on the line 6—6, Fig. 4;

50 In the drawing 1 indicates a portion of a mattress, cushion or other article and 2 indicates a loop of tufting cord or tufting tape which has been inserted in the mattress. This loop comprises the two side portions 3 and 4 which extend through the mattress or other article 1 and are

spaced from each other, the ends of the loop being tied together on one face of the mattress as shown by the knot 5. This loop of tufting cord presents the portion 6 which is exposed on one face of the mattress and the portion 7, having the 60 knot 5 therein which is exposed on the other face of the mattress. The portion 6 of the tufting cord will, of course, be free of knots.

It is frequently desirable to apply a tufting button not only to the exposed knotless portion 6 of 65 the loop 2 on one side of the mattress but also to the knotted portion 7 of the loop on the other side of the mattress and the tufting button which forms the subject of the present invention has been designed so that it can be as readily applied 70 to the knotted portion 7 of the loop as to the knotless portion 6. Moreover, my improved tufting button is of such a character that when it is applied to the knotted portion 7 of the loop the knot 5 will be confined within the button and will 75 thus be concealed from view.

A tufting button embodying my invention is indicated generally at 8 and it is herein shown formed with the back portion 9 and with the front portion 10, both portions being made of 80 sheet material and being connected together in usual manner along the periphery of the button as shown at 11.

The back 9 of the button is formed with an opening 12 of a size to readily admit the knot 85 5 and it is also formed with cord-retaining fingers extending outwardly from the back on two opposite sides of said opening 12, said fingers being indicated at 13 and 14 respectively. On each of the other two opposite sides of the opening 12, to wit, the sides indicated at 15, the back is deformed to present a cord-receiving 90 groove 16 which leads into the opening 12.

The fingers 13 and 14 are bendable from their open position shown in Figs. 3 and 5 into their closed or cord-retaining position shown in Figs. 4 and 6 and when they are bent into their closed position said fingers fill the opening 12. For this purpose the fingers 13 on one side of the opening 12 have a staggered arrangement with 100 relation to the fingers 14 on the opposite side of the opening. Said fingers may conveniently be formed by providing a zig-zag slit in the back 9 of the button as shown at 17 in Fig. 4 and then bending the portions indicated at 13 in Fig. 4 outwardly to form the fingers 13 and similarly bending the portions indicated at 14 in Fig. 4 outwardly to form the fingers 14. The bending 105 of these portions 13 and 14 outwardly from the 110

back of the button produces an opening 12 as will be obvious.

In applying the tufting button to the tufting cord one set of fingers, to wit, the fingers 13 or the fingers 14, is inserted underneath the exposed portion of the loop, whether the knotless exposed portion 6 or the knotted exposed portion 7, and the button may be manipulated so that it will occupy a position between said exposed portion of the loop and the mattress with the front of the button against the mattress and the fingers 13, 14 projecting outwardly. If the button is being applied to the knotted portion 7 of the loop this operation will result in placing the knot 5 in the opening 12 in the back of the button. The fingers 13 and 14 are then bent downwardly from their open position shown in Figs. 3 and 5 into the closed position shown in Figs. 4 and 6 thereby attaching the button to the loop and thereafter the button may be turned about the exposed portion of the loop to bring the face of the button into an exposed position and to carry the back of the button against the mattress. When the button has been thus attached to the mattress the loop of tufting cord or tufting tape passes through the grooves 16 into the interior of the button and extends behind the closed fingers 13 and 14.

The provision of the opening 12 which is subsequently closed by the fingers provides a tufting button which can be readily applied to the knotted portion 7 of a tufting cord or tufting tape and when it is so applied the knot 5 will be within the button. If the button is of the type having a front portion then the knot is entirely concealed from view but if the tufting button is of the type which comprises simply the back portion 9 then, of course, the knot would still be exposed.

40 I claim:

1. A tufting button having an opening in its

back, cord-retaining fingers extending from said back on two opposite sides of the opening, said fingers being bendable from their open position into a cord-holding position in the plane of the back and when in the latter position filling the opening. 80

2. A tufting button having an opening in its back, and cord-retaining fingers extending from said back on two opposite sides of the opening, said back being formed to present a cord-receiving groove on each of the other two opposite sides of said opening, said fingers being bendable from their open position into a cord-holding position in the plane of the back and when in the latter position filling the opening. 85

3. A mattress or the like having a loop of tufting cord extending therethrough with the sides of the loop spaced from each other and the ends of said sides tied together in a knot located on the exterior surface of the mattress, a tufting button formed in its back with an opening of a size to receive said knot and with cord-receiving grooves leading into the opening on two of the opposite sides thereof, cord-retaining fingers extending from the other two opposite sides of said opening, said fingers extending between the knotted portion of the loop and the mattress and having an interleaved relation and also filling said opening, whereby the knot of the loop is located on the interior of the button. 90

4. A tufting button comprising a back portion of sheet material provided with a zig-zag slit thereby forming two series of interleaved fingers which when bent outwardly from the back form an opening between them with the fingers projecting from the back on opposite sides of the opening, said back being formed on the other two opposite sides of the opening with a cord-receiving passage leading to said opening. 100
